UNITED STATES PATENT OFFICE.

ANNA OLSSON, OF SOUTH MANCHESTER, CONNECTICUT, ASSIGNOR TO CHENEY BROTHERS,
OF SOUTH MANCHESTER, CONNECTICUT, A CORPORATION OF CONNECTICUT.

DESIGN FOR A TEXTILE FABRIC.

No. 38,909.

Specification for Design.

Patented Nov. 26, 1907.

Application filed September 21, 1907. Serial No. 394,002. Term of patent 3½ years.

To all to whom it may concern:

Be it known that I, ANNA OLSSON, a citizen of the United States, residing at South Manchester, in the county of Hartford and State of Connecticut, have invented a new, original, and ornamental Design for Textile Fabrics, of which the following is a specification, reference being had to the accompanying drawing, forming part thereof.

The figure is a plan view of the fabric, showing my new design.

I claim:

The ornamental design for a textile fabric, as shown.

ANNA OLSSON.
